Primary Examiner — Philip S Hyder(57) **CLAIM**

The ornamental design for a selectable twist tool, as shown and described.

DESCRIPTION

FIG. 1 is a top-front perspective view of a selectable twist tool showing our new design;

FIG. 2 is a top-rear perspective view thereof;

FIG. 3 is a front elevational view thereof;

FIG. 4 is a rear elevational view thereof;

FIG. 5 is a right-side elevational view thereof;

FIG. 6 is a left-side elevational view thereof;

FIG. 7 is a cross-sectional view taken along line 7-7 in FIG. 6;

FIG. 8 is a top plan view thereof;

FIG. 9 is a bottom plan view thereof; and,

FIG. 10 is a cross-sectional view taken along line 10-10 in FIG. 9.

The broken lines showing the tool body in FIG. 1-10 are included for the purpose of showing environmental structure and form no part of the claimed design. The selectable twist tool is shown with a symbolic break in its length in FIGS. 1-2 and 5-10. The appearance of any portion of the article between the break lines forms no part of the claimed design.
